Primary Examiner — Patricia A Palasik*(74) Attorney, Agent, or Firm* — Schroeder & Siegfried, P.A(57) **CLAIM**

The ornamental design for an oxygen acetylene torch cutting handle with flush mount trigger, as shown and described.

DESCRIPTION

FIG. 1 is a perspective view of an oxygen acetylene torch cutting handle with flush mount trigger showing my new design;

FIG. 2 is a front elevational view;

FIG. 3 is a rear elevational view;

FIG. 4 is a right side elevational view;

FIG. 5 is a left side elevational view;

FIG. 6 is a bottom plan view;

FIG. 7 is a top plan view;

FIG. 8 is a perspective view of an alternative embodiment of an oxygen acetylene torch cutting handle with flush mount trigger.

FIG. 9 is a front elevational view;

FIG. 10 is a rear elevational view;

FIG. 11 is a right side elevational view;

FIG. 12 is a left side elevational view;

FIG. 13 is a bottom plan view; and,

FIG. 14 is a top plan view.

The broken lines in the drawings represent environmental structure and form no part of the claimed design.

1 Claim, 10 Drawing Sheets---
